Leo G. Schussmann INVENTOR

UNITED STATES PATENT OFFICE.

LEO G. SCHUSSMANN, OF SHEBOYGAN, WISCONSIN.

ADJUSTABLE CHAIR.

No. 892,315.

Specification of Letters Patent.

Patented June 30, 1908.

Application filed February 15, 1907. Serial No. 357,494.

To all whom it may concern:

Be it known that I, LEO G. SCHUSSMANN, a citizen of the United States, residing in Sheboygan, in the county of Sheboygan and 5 State of Wisconsin, have invented a certain new and useful Improvement in Adjustable Chairs, of which the following is a specification.

The improvement may apply to a great 10 variety of styles of chairs. I will show a plain and simple form. It is firm in resisting any backward force imparted by the sitter or by any other person, but it is always ready to be shifted forward. 15 There may be ornaments and additional mechanism for any purpose, but the object of my invention is to avoid the necessity for mechanism and also for any consumption of time and for any considerable labor in effecting the adjustment, and reliably and strongly holding the back in any required position. 20 The user of the chair can, by simply leaning forward and then shifting it rearward and partly forward again, effect a complete and 25 strong adjustment.

The movements are easily made and the operator may remain seated through the whole of the very brief period required. It absolutely forbids any displacement rearward, except after an unusual extreme forward movement. There will usually be sufficient friction, or there can be easily imparted sufficient, to prevent its being shifted forward too easily. I provide means for delicately adjusting the conditions so as to 35 change the action when required.

The accompanying drawings form a part of this specification.

Figure 1 is a side elevation of the chair 40 adjusted, and Fig. 2 is a vertical section on the line 2--2 in Fig. 1. The remaining figures down to Fig. 9 are diagrammatic. They show the working parts in side elevation in the several relations which they assume at 45 different periods. Fig. 3 is a side elevation corresponding to Fig. 1. It shows the parts adjusted—it is desired to readjust with the back at a greater inclination. Fig. 4 is a side elevation showing the back pulled forward to its extreme front position. Fig. 5 is a corresponding elevation showing it in a middle position in the act of being moved idly backward or as I prefer to term it, rearward. Fig. 6 shows the back in its extreme 55 rearward position. Fig. 7 shows the back being moved slowly forward. Fig. 8 shows

the slow forward movement arrested, and Fig. 9 shows the chair-back again pressed rearward by a person sitting in the chair and bearing back, or by any other means. All 60 these are side elevations. Fig. 10 is a plan view of the movable plate detached, seen from below.

Similar letters of reference indicate corresponding parts in all the figures where they 65 occur.

A is the rigid body of the chair, B is an adjustable back and B¹ the line of the pivots serving as the center therefor.

C is a stout pawl, which I will refer to as 70 the dog, pivoted at C¹ to the lower end of the back B, and arranged to present its working end C² in the proper relation to engage with a succession of teeth A¹, formed on the under side of the chair seat, or on a suitable bar 75 introduced to carry such teeth.

D is a spring mounted on the fixed frame work of the chair urging the dog upward.

E is a movable plate extending forward and backward in the chair under the teeth 80 A¹ and free to move endwise to a limited extent. I have shown the guidance and this limiting as both effected by the same means,—two bolts or studs G and H set in the lower side of the seat A, adjacent to the teeth A¹. 85 These studs have heads which lie below and their bodies extend upward through a slot e in the plate E. The heads G¹ H¹ support the plate E and both the bodies G and H serve as guides for the plate and also as stops 90 meeting the ends of the slot e whenever the plate is moved endwise until they are struck.

K is a pawl which may be quite light pivoted to C at K¹ carrying a hook K² and a swell K³. It is pressed upward by a spring 95 L abutting on the dog C. One end K¹, the front end, is knuckled to a point near the midlength of the dog C. The free end, the rear end, is hook-formed as indicated. The proportions of these several parts being 100 about as shown, the stout pawl or dog C reaches up past the front end of the plate E (see Fig. 3) and engages in one of the notches A¹ and holds the back firmly against being pressed rearward any further. But when 105 sufficient force is applied in the direction to pull the chair-back forward, it yields thereto, thereby drawing rearward the dog C, and by the pressure of its inclined surface C² against the front edge of the plate E, causes that 110 plate to gently but reliably move rearward therewith. The back can thus be shifted for-

ward at any time, to any extent desired and on being released will be held in the new position by the dog C engaging in a different notch.

5 When the back, rocking on the axis B¹ is drawn forward to its extreme forward position, its lower edge has moved rearward and a new condition obtains. The plate E has been arrested by the screw G being received 10 in the front end of the slot e and cannot move further rearward. Now the extreme forward motion of the back B draws the dog C further rearward and its smooth inclined surface C² pressed against the front edge of 15 the plate E is drawn downward against the force of the spring D and commences to ride under the plate E. This condition is shown in Fig. 4. The same movement of the dog C rearward and slightly downward carried 20 further has presented the hook pawl K in such position that being pressed upward by the spring L its hook K² has engaged with the rear end of the plate E. Now while the parts remain in this condition, the back B of 25 the chair may be moved rearward freely;— the dog C does not forbid it because that dog is held down out of action by the interposed plate E. The sitter can now, if he chooses, move the chair-back at once through the 30 whole range of its motion to the extreme backward position. I will describe it as thus worked. This first movement rearward, at once or more moderately, makes the hook K² let go of the plate E (see Fig. 6). It 35 does this by bringing the rounded swell K³ of the hook K² into contact with the rounded head J¹ of the screw J which screw extends, otherwise idly, through the slot e. This is certain to occur at a late stage of the movement 40 and may occur much earlier if the screw J is adjusted low enough. Any time a second forward movement of the back, and consequent rearward movement of the dog, may be made after such disengagement of 45 the hook pawl, and the hook K² being no longer engaged, the plate E will remain in its forward position, or it may move rearward, but it is idle, and the whole series of notches A¹ are exposed and ready to be engaged in 50 succession by the dog C. With the parts thus favorably conditioned (see Fig. 7) he brings the back B cautiously forward, the dog C snapping successively into the several notches A¹. When he has reached the angle 55 of the back which suits him, he stops and on leaning back in the chair, or otherwise moving the back rearward enough to take up the slack, the adjustment is completed.

The screw J with its head J¹ should be a 60 screw equipped with an ordinary score for allowing the screw to be turned by a screw-driver and screwed upward so as to be less prominent or unscrewed so as to be more prominent, in order to act on the swell K³

just right. It must allow the hook K² to 65 keep engaged during the first part of the rearward movement of the back in adjusting and be certain to liberate it at the extreme rearward position.

The operation being peculiar a repetition 70 in different words may be allowable. In the normal upright position of the back, as shown in Fig. 3, the dog C is held in engagement with the teeth A¹ by the spring D, and the pawl K is held in inoperative position 75 against the underside of the plate E by the spring L. Assuming the dog C to be now in engagement with the most rearward tooth A¹, in order to secure a different inclination 80 of the back, the latter must be moved forward as shown in Fig. 4 whereupon the inclined surface C² engages the front edge of the plate E, causing such plate to move rearwardly. This is continued until the plate has reached its rearward limit of movement. 85 Further forward movement of the back causes the end C² to be depressed and to slide beneath the plate E and soon after the pawl K to engage the rear of the plate E which position is shown in Fig. 4. The back can now 90 be swung rearwardly, as in Fig. 5, the plate E being moved forwardly by the pawl K and holding the end C² out of engagement with the teeth A¹. When the back has nearly reached its limit of rearward movement the 95 swell K³ engages the head J¹ of the screw J and thereby the pawl K is thrown out of engagement with the plate. Further rearward movement causes the end C² to engage the forward tooth A¹ as in Fig. 5. The back can 100 now be adjusted forwardly step-by-step, the plate E being moved rearwardly by the dog C, as shown in Figs. 7, 8 and 9.

Modifications may be made without departing from the principle or sacrificing the 105 advantages of the invention.

The number and size of the teeth A¹ may be varied. It may be ordinarily preferable to duplicate the construction and have one 110 on each side of the chair.

The rounded-head J¹ may be fixed instead of adjustable. Any other piece may be substituted for it, taking care that it is presented at a proper stage of the motion of the chair-back to disengage the hook-pawl K from the 115 plate E.

Although I have used the term "chair" in the title for brevity, and have described the invention as applied to a chair, so called, it is obvious that it may be made to apply to the 120 longer structures we call lounges.

I claim as my invention:

1. In an adjustable chair, the combination with a body provided with teeth, of a back movably connected thereto, a dog adapted to 125 engage said teeth and said back and operated by the latter, a hook pawl engaging said dog, a shield plate for the teeth movably connect-

ed to said body and operated by said dog and said pawl and means for engaging and disengaging said pawl and said shield plate.

2. In an adjustable chair a chair-body carrying a series of teeth, an adjustable back pivoted to the body and carrying a dog adapted to engage with such teeth, a spring for yieldingly urging such dog upward a plate mounted between adapted to permit such engagement or to keep the dog out of the engagement according as such plate is placed, a hook pawl carried by said dog and a spring for yieldingly urging such pawl into engagement with such plate.
- 15 3. An adjustable chair comprising a chair-body carrying a series of teeth, an adjustable back pivoted to the body and carrying a dog adapted to engage with such teeth, a plate mounted between, and a hook pawl pivoted to such dog, the two being adapted to move the plate forward and backward.
- 25 4. An adjustable chair comprising a chair-body carrying a series of teeth, an adjustable back pivoted to the body and carrying a dog adapted to engage with such teeth, a plate adapted to permit or forbid the engagement of the dog according as it is placed, a hook pawl operated also by the chair-back for operating the plate in one direction and provisions for engaging the hook with the plate at one end of its motion and for detaching the

hook from the plate before it has reached the other end of its motion.

5. An adjustable chair comprising a chair-body carrying a series of teeth, an adjustable back pivoted to the body and carrying a dog adapted to engage with such teeth, a plate adapted to permit or forbid the engagement of the dog according as it is placed a hook pawl pivoted to such dog and a screw J J¹ set adjustably in the chair-body adapted to contact with the such pawl and effect the disengagement thereof from the plate when required.

6. A chair-body A, series of stationary teeth A¹, adjustable back B, dog C operated by the back and engaging in said teeth a hook pawl pivoted to such dog and a plate E serving under some conditions to prevent such engagement, and screws G H extending through the slot e in such plate having heads G¹ H¹ arranged to serve the double functions of guides and stops for the plate and the screw J J¹ which performs the duty of detaching the hook pawl at easily adjustable points.

Signed at Sheboygan, Wisconsin, this 4th day of February 1907.

LEO G. SCHUSSMANN.
